SOLDERER OR LEAD TOOL

Harry Abramson, Ventnor, N. J.

Application July 22, 1943, Serial No. 495,756

1 Claim. (Cl. 219—27)

This invention relates to a solderer or lead tool especially adapted for safely converting such materials into liquid form and for the dispensing thereof as need therefor occurs.

The primary object of the invention is the provision of a device of the stated character which is simple to operate and convenient to handle and which will permit a person through the use of one hand to easily and quickly dispense the liquefied lead or solder in desired amounts while the other hand may be employed for other work.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

The figure is a side elevation, partly in section, illustrating a solder or lead tool constructed in accordance with my invention.

Referring in detail to the drawing, the numeral 5 indicates an elongated housing which has one end closed and its opposite end reduced to form an attaching neck 6 both externally and internally screw threaded. A tubular chamber 7 has one end threaded in the neck and extends well into the housing toward the closed end thereof. One end of the tubular chamber is closed and is provided adjacent said closed end with a filling port controlled by a door 8 provided in one side of the housing. The door is of the hinged type and held in a closed position by a latch 9, preferably of the pivoted type. The space between the tubular chamber 7 and the housing accommodates an electric heating unit 10 of a conventional construction suitably insulated from the housing as well as the tubular chamber, as shown at 11. The electric leads 12 of the electric heating unit have connected therein a standard type control switch 13 located within a chamber 14 formed in a handle extension 15 of the housing. The handle extension is formed on one side of the housing close to the closed end thereof and is in the form of a pistol grip.

While the housing 5 with its angular handle extension 15 may be in the general form shown and in a substantially integral structure, it is obvious that the housing portion proper 5 may be divided in any suitable manner either crosswise or longitudinally or in segmental sections whereby one or more sections may be detached to fa-

cilitate the assembly of the tubular chamber 7, electrical heating unit 10 and the insulation 11, as well as any other of the internal parts of the device. As such sectional provision for the housing 5, in itself, is not a part of the present invention, the same is not illustrated in detail in the drawing.

The electric leads extend from the chamber 14 in the form of an extension cord having an electric fitting 16 to permit its connection and disconnection to an electric output.

A trigger 17 is pivoted to the handle 15 and is spring influenced, as shown at 18. The trigger connects with the switch for the operation thereof and when it is desired to complete the electric circuit to the electric heating unit 10 the trigger 17 is squeezed and as soon as released the spring 18 returns the trigger to its initial position to permit the switch to open and break the circuit.

A nozzle 19 threads onto the neck or fitting 6 and is provided with a passageway 20 connecting with the chamber 7. The passageway 20 is reduced in diameter towards its outer end and extends through the free end of the nozzle, and mounted in the passageway adjacent the free end of the nozzle is a valve seat 21 engaged by a valve element 22 that includes an extension 23 protruding a limited distance beyond the free end of the nozzle. The valve element is held in a seated position by a spring 24 of the coil type bearing against the valve element and against a spider 25 threaded in the nozzle or the passage thereof.

The extension 23 protruding beyond the free end of the nozzle may be brought into engagement with an object for the purpose of unseating the valve.

In operation, lead or solder is arranged within the chamber 7 by being placed therein when the door is in an open position, after which the door is obviously closed leak-tight. The switch is then closed by squeezing the trigger 17 energizing the electric unit 10 so that the heat therefrom will melt the solder or lead reducing it into liquid form. The operator may then dispense the liquefied lead or solder through the nozzle onto or into an object by pressing the extension 23 against the object, thus permitting the person to control the amount of liquefied solder or lead dispensed and also permit the person to direct the liquefied solder or lead onto or into an object without spilling or waste. This device being electrically heated and suitably insulated will reduce fire hazards to a minimum and allow the dis-

pensing of lead or solder in liquid form and in desired amounts through the use of one hand, leaving the other hand free to carry out other work.

As soon as the switch 13 is permitted to open by releasing the grip on the trigger 17, the device will begin to cool and when cold the lead or solder becomes solidified and remains in that condition until the tool is again placed in use or the circuit to the electric unit is again closed.

While I have shown and described the preferred embodiment of my invention, it will be understood that minor changes in construction, combination and arrangement of parts may be made without departing from the spirit and scope of the invention as claimed.

Having thus described my invention, what I claim is:

In a tool of the character described, a handled enclosure shell or housing having its end portion remote from its handled portion open and reduced to form a cylindrical neck which is externally screw-threaded, an axial tubular solder or lead-containing and melting chamber having its open end portion fitted and supported leak-tight

5 within said neck portion of the outer shell or housing, said tubular chamber extending with its closed opposite end portion substantially rearward in said shell or housing, an electrical heating element surrounding said tubular chamber within the shell or housing and electrically insulated from both the tubular chamber and the shell or housing but with heating effect on said chamber, and a detachable dispensing nozzle for liquid solder or lead having an enlarged open end portion internally screw-threaded to fit the external screw threads on said neck portion of the shell or housing and provided with a tapered longitudinal chamber communicable at its larger end with said solder or lead containing and melting chamber, said nozzle having a substantially reduced tapered tip extension having a restricted bore therethrough communicating at its inner end with said tapered chamber of the nozzle, and a spring-urged normally closed but inwardly opening valve in the outer end portion of said nozzle tip, said valve having an axial stem projected outwardly beyond the end of the tip extension of the nozzle.

HARRY ABRAMSON.
